(57) **CLAIM**

The ornamental design for a bottle, as shown and described.

DESCRIPTION

FIG. 1 is a top, front, and right side perspective view of a bottle depicting the new design;

FIG. 2 is a front elevational view thereof;

FIG. 3 is a rear elevational view thereof;

FIG. 4 is a top plan view thereof; and

FIG. 5 is a bottom plan view thereof; and,

FIG. 6 is a top plan view thereof, with no environment being shown.

The broken lines shown in FIGS. 1-5 are for illustrative purposes only and form no part of the claimed design.
